UNITED STATES PATENT OFFICE.

JAMES B. ARTHUR, DECEASED; BY MARY R. ARTHUR, EXECUTRIX, OF JOPLIN,
MISSOURI.

ORE CONCENTRATOR.

Original application filed February 21, 1920, Serial No. 360,434. Divided and this application filed
May 15, 1922. Serial No. 560,883.

To all whom it may concern:

Be it known that I, MARY R. ARTHUR, a citizen of the United States, residing at Joplin, in the county of Jasper and State of Missouri, have been appointed executrix of the last will and testament of JAMES B. ARTHUR, late a citizen of the United States, deceased, who invented certain new and useful Improvements in Ore Concentrators, of which the following is a specification.

This invention relates to ore concentrators and the present application is a division of the copending application Serial No. 360,434 Feb. 21, 1920. The principal object of the present invention is to provide means for feeding the crushed ore and distributing the same in a more uniform manner than heretofore over the rotary table upon which the concentrates are collected, to the end that more of the concentrates may be recovered than heretofore.

In order that the invention may be fully understood, reference will now be had to the accompanying drawings, in which:

Fig. 1 is a front elevation of the concentrator equipped with the feeding and distributing mechanism.

Fig. 2 is an enlarged broken vertical section on line II—II of Fig. 1, with some of the parts removed.

Fig. 3 is an enlarged, fragmentary cross section on line III—III of Fig. 2.

Fig. 4 is an enlarged fragmentary cross section on line IV—IV of Fig. 2.

Referring now in detail to the various parts, 2 designates a suitable frame, in the center of which a vertically-disposed shaft 4 is mounted. Said shaft 4 is journaled at its upper portion in a bearing 6 and at its lower end in a step bearing 8.

10 designates a rotary table having a flat bottom portion upon which the crushed ore is fed, and a centrally-disposed hub 12 keyed or otherwise fixed to the shaft 4 in order to rotate therewith.

The table 10 is provided with a fixedly-mounted centrally-disposed drum 50, which is surmounted by a conical distributor 52 fixed to the lower end of a tubular shaft 54, 50 journaled on the shaft 4 and resting upon a collar 56 fixed to said shaft 4. The margin of the distributor 52 is surrounded by an annular guard 58 supported by arms 60 secured to the periphery of the drum 50. As

shown more clearly on Fig. 2, the guard 58 is spaced from the circular margin of the distributor 52 to leave an annular space 61 for the passage of the crushed ore from said distributor 52 to the table 10.

62 designates a rotary hopper disposed above the distributor 52 and supported by hangers 64, adjustably connected at their upper ends to a sleeve 66 having a groove-and-feather connection 68 with a tubular shaft 70, journaled upon the tubular shaft 54 and resting upon a flange 72 fixed to said tubular shaft 54.

The hopper 62 may be raised and lowered to vary the space between its discharge end and the distributor 52, by means of a lever 74 operably connected at its bifurcated end to a band 76, loosely mounted in a peripheral groove in the sleeve 68 to permit said sleeve to rotate without rotating the band 76 and said lever 74. The lever 74 is mounted upon a fulcrum 78, carried by an arm 79 having a notched segment 80 whereby the lever 74 is held in any of its adjusted positions.

The shaft 4, carrying the table 10 is provided at its upper end with a bevel gear 82 meshing with a bevel gear 84, fixed upon a drive shaft 86 journaled in bearings 88 on top of the frame 2 and provided with fixed and loose pulleys 90 and 92, respectively.

The tubular shaft 54 is provided at its upper end with a bevel gear 94 intermeshing with a bevel gear 96 fixed upon a counter shaft 98 provided with another bevel gear 100, intermeshing with a bevel gear 102 fixed upon a vertical shaft 104 provided at its upper end with a bevel gear 106 driven by a bevel gear 108 loosely mounted upon the drive shaft 86.

The tubular shaft 70 is provided at its upper end with a bevel gear 110 intermeshing with a bevel gear 112 fixed upon a countershaft 114 provided with another bevel gear 116 driven by a bevel gear 118 fixed upon the lower end of the vertical shaft 104, which is journaled in a bracket 120 depending from the frame 2. The counter shafts 98 and 114 are journaled in hangers 122 and 124 depending from the upper portion of the frame 2. The hanger 122 carries the notched segment 80 and is provided with a bearing 126 surrounding the tubular shaft 70.

The bevel gear 108 is loosely mounted upon the drive shaft 86 but may be caused to rotate therewith at will through the intermediary of a clutch 130 having a groove-and-feather connection 132 with said drive shaft 86 and controlled by a hand lever 134.

In the practical operation of the machine, the clutch 130 is shifted into engagement with the bevel gear 108 to drive the distributor 52 and the hopper 62 in reverse directions to each other through the intermediary of the intervening gearing when power is applied to the fixed pulley 90. The table 10 is driven in the same direction as the hopper 62 through the intermediary of the gears 84 and 82. The crushed ore is conducted to the hopper 62 by a chute 63 or other suitable conveyer and as said hopper 62 rotates, it discharges the ore upon the distributor 52, which in turn discharges it uniformly upon the table 10. As the ore falls upon the distributor 52 the guard 58 prevents said ore from being cast off by centrifugal force and directs it downwardly around the drum 50 from where it spreads evenly over the table 10. If it is desired to feed the ore rapidly to the distributor 52, the hopper 62 is raised by proper manipulation of the lever 74 to increase the size of the opening between the lower end of said hopper 62 and the top of the distributor 52, and if a slower feed is desired the hopper 62

is lowered to reduce the size of the opening. As the crushed ore and the accompanying water flow outwardly upon the table 10 towards the rim 16, the water being lighter than the ore is forced to the top and escapes through spouts 26 as fully set forth in the parent application above-mentioned. After the ore attains the desired depth upon the table 10 the belt is shifted from the tight pulley 90 to the loose pulley 92 to bring the moving parts to a stop.

Having thus described my invention, what I claim and desire to secure by Letters Patent, is:

In an apparatus of the character described a rotary table having a flat bottom portion and rim fixed thereto; a centrally disposed drum fixed to said table, a conical distributor spaced above and overlapping said drum, a guard spaced from and encircling said distributor, means supporting said guard and secured to the drum, and means for continuously driving the table and the distributor in opposite directions.

In testimony whereof, I affix my signature in the presence of two witnesses.

MARY R. ARTHUR,
Executrix of James B. Arthur, Deceased.

Witnesses:

BERTHA ISAACS,
H. J. EISENBACH.
